UNITED STATES PATENT OFFICE.

FRANKLIN JOSEPH WHITNEY AND PHILLIP SHURDEN HALL, OF BREDENBURY,
SASKATCHEWAN, CANADA.

COMBINED CAR-CHECKER'S LAMPS AND BOOK HOLDER.

1,180,460.

Specification of Letters Patent. Patented Apr. 25, 1916.

Application filed March 29, 1915. Serial No. 17,620.

To all whom it may concern:

Be it known that we, FRANKLIN JOSEPH WHITNEY and PHILLIP SHURDEN HALL, both of the town of Bredenbury, Province of 5 Saskatchewan, Canada, and both subjects of the King of Great Britain, have invented certain new and useful Improvements in a Combined Car-Checker's Lamps and Book Holder, of which the following is a specification.

Our invention relates to improvements in combined car-checker's lamps and book holder, and the object of our invention is to provide a device containing lamps and a book, which device when opened, will throw light against a car to illuminate the numbers thereof, and to illuminate the seals on the car doors, and at the same time illuminate the book whereby the car checker keeps his records, and the construction of our invention will be hereinafter set forth and what we claim as new will be pointed out in the claims forming part of this specification.

25 Figure 1 is in part a vertical longitudinal section through our device showing internal construction, and in part an end elevation of the battery case, portion of the cover being shown open and in dotted lines. Fig.
30 2 is a plan view of our device, certain parts being broken away, and shown in section to illustrate internal construction. Fig.
35 3 is a vertical longitudinal section through the rear portion of the cover showing construction of same.

In the drawings, like characters of reference indicate corresponding parts in each figure.

40 It is well known that car checkers have to keep record of the numbers on cars, as well as to inspect the condition of the seals sealing the car doors, and this operation has to be carried out in all kinds of weather at night time as well as during the day time.

45 It is very awkward for the car checker to make entries in his book and at the same time hold a light to illuminate the necessary parts of the car at night time, and one of the chief objects of our invention is to provide a device which, when opened, will light two lamps, one in the top of the cover to throw a light on the car, and the other in the inner side of the cover to illuminate the book.

55 A is any suitable battery case in which

is mounted any suitable source of electric current, for instance a dry battery composed of two cells B and C. Coupled to said battery case is a member D forming the base of the apparatus. This member is secured to the battery case A by any suitable means. A suitable coupling means we illustrate is composed of a metal member E suitably secured to the battery case A and secured by rivets F or any other suitable means to the base D. The cover G may be of any suitable construction, and the same is provided with side flanges H and a front flange I. These flanges fit around the sides of the base D, and together with the top of the cover make the apparatus weather-proof so as to keep the book J from the rain. The rear ends K of the side flanges H are concaved as shown in Fig. 3, particularly so that the cover will fit closely against the battery case A. The cover is hinged to the battery case A by a plurality of hinges L through the medium of the top M thereof. To provide room for the lamp N, the top M is constructed with tapered sides substantially as shown in Figs. 1 and 2, so that the connections for the lamp N may be positioned within the cover and free from the weather.

2 and 3 are plates forming part of the 85 cover and spaced apart, and mounted in the plate 2 is a socket 4 for the electric lamp 5, the shade 6 of which is preferably held in the plate 3 and projects therethrough. The plate 2 may be omitted and the lamp 5 90 mounted in the plate 3 as before described, but the use of the two plates firmly support the lamp. The plates 2 and 3 are preferably made of metal not only to strengthen the construction of the cover, but also to 95 prevent the light from either lamp interfering. When the cover is moved into the dotted position illustrated in Fig. 1, the circuit is closed, thus lighting the lamps. The lamp N throws the light against the car, 100 and lamp 5 throws the light to illuminate the book L.

7 is a metal contact strip secured to the battery casing A, and 9 is a metal contact strip forming a contact pole secured to the end 10 of the cell C. Suitably carried by one of the side flanges H of the cover is a metal strip 11 which, when the cover is moved into the dotted position illustrated in Fig. 1, performs the function of a switch 110

by coming into contact with the contact strips 7 and 9 so as to close the circuit for the lamps hereinafter particularly set forth. Secured to one end of the battery case A 5 is a spring 12 the free end 13 of which rests in contact with the pole 14 of the cell B, and the function of this spring is to keep the pole 15 of the cell B in contact with the pole 16 of the cell C. The switch 11 10 always extends in front of the outer end of the cell C so as to assist in preventing the cells from dropping out of the battery case A, and since the inner ends of the contact strips 7 and 9 are beveled, the switch 11 15 will always ride over the outer sides of the said contact strips when the cover is open. It is designed that the cells B and C shall fit fairly tightly in the battery case A, so that we will not have to depend entirely on the switch 11 to retain them therein.

We shall now describe a suitable circuit for the lamps. We will suppose that the switch 11 is in contact with the contact strips 7 and 9. Therefore the current passes from the pole 10 through the contact pole or strip 9 carried thereby to the switch 11, and from this switch it passes into the contact strip 7, which is wired by the wire 17, to the leaf 18, of one of the hinges and thence 20 through the other leaf 19 along the wire 20 to the binding post 21 of the lamp 5, thence through the wire 22 to the binding post 23 of the lamp N; out of this lamp by the binding post 24 and wire 25 to the binding post 26 of the lamp 5 and thence through the wire 27 to the leaf 28 of another of the hinges, and through the leaf 29 and wire 30 to the binding post 31 of the switch 25 plate 32; through the switch 33 and binding post 34, through the wire 35 to the end 13 of the spring 12, thence through the poles 14, 15 and 16 to the pole 10. It will therefore be understood that as long as the switch 33 is closed, the lamps N and 5 will 40 immediately be lighted, and so soon as this cover is closed far enough the circuit will be opened to extinguish said lamps.

In order to prevent the waste of current 50 particularly during the day time when it will not be necessary to light the lamps, the switch 33 is provided which can be used to open the circuit.

The hinges mentioned as being included 55 in the circuit are of course insulated from the case A if this case be made of metal. If the same be made of red fiber or equivalent material, of course special insulation for the hinges will not be necessary.

60 By utilizing the hinges as part of the circuit, we prevent the breaking or entanglement of the wires as the cover opens and closes.

Any suitable clamping means may be provided for the book J. A suitable clamping

plate 36 is shown secured to the base D by the rivets F and the head 37 of this clamping plate is formed to provide a groove 38 in which his held the stud 39 of the book J.

40 is a spring plate upon which the inner portion of the book is placed, and as the inner end 41 of said spring plate operates adjacent the clamping plate 36, it co-acts with the head 37 to retain the stud 39 in place. Any suitable means such as screws 75 42 may be used to secure the spring plate 40 in position.

Any suitable catch mechanism particularly illustrated in Fig. 1, for instance the spring lip 43, may be used to co-act with 80 the plate 44 to hold the cover closed.

It is obvious that the principle of our invention may be embodied in different forms without departing from the spirit thereof and therefore we do not confine ourselves to the construction described and shown except in so far as this may be rendered necessary by the prior state of the art and the terms of our claims.

What we claim as our invention is:

1. An article of the class described comprising a suitable base; a movable cover having hinge-connection with said base; an electric lamp mounted in said cover and positioned to illuminate said base, another electric lamp mounted in said cover in position to direct light beyond the cover; a source of electrical energy carried by said base; a suitable circuit for said lamps connected with said source of electrical energy, and means whereby when said cover is opened far enough said circuit will be closed to light said electric lamps. 90 95 100

2. An article of the class described comprising a suitable base; means whereby a book may be clamped to said base; a movable cover designed to inclose said book and having hinge-connection with said base; an electric lamp mounted in said cover and positioned to illuminate said book; another electric lamp mounted in said cover in position to direct light beyond the cover; a source of electrical energy carried by said base; a suitable circuit for said lamps connected with said source of electrical energy, and means whereby when said cover is opened far enough said circuit will be closed to light said electric lamps. 105 110 115

3. An article of the class described comprising a suitable base; a battery case coupled to said base and containing a suitable battery; a cover having hinge-connection with said battery case; an electric lamp mounted in said cover and positioned to illuminate said base; another electric lamp 120 125 mounted in said cover and positioned to direct light beyond the same; a suitable circuit connecting said lamps with said battery, and a suitable switch carried by said cover designed to close said circuit when 130

said cover is opened far enough to light said lamps.

4. An article of the class described comprising a suitable base; a book positioned on said base; suitable clamping means carried by said base to clamp said book in position; a battery case coupled to said base and containing a suitable battery; a cover having hinge-connection with said battery case; an electric lamp mounted in said cover and positioned to illuminate said base; another electric lamp mounted in said cover and positioned to direct light beyond the same; a suitable circuit connecting said lamps with said battery, and a suitable switch carried by said cover designed to close said circuit, when said cover is opened far enough, to light said lamps.

5. An article of the class described comprising a suitable base; a battery case coupled to said base and containing a suitable battery; a cover having hinge-connection with said battery case and provided with a horizontally disposed plate, and further provided with a top member which projects above said plate; an electric lamp mounted in said plate in position to illuminate said base; another electric lamp mounted in said top member and positioned to direct the light beyond the same; a suitable circuit con-

necting said lamps with said battery, and a suitable switch carried by said cover designed to close said circuit, when said cover is opened far enough, to light said lamps.

6. An article of the class described comprising a suitable base; a battery case coupled to said base and containing a suitable battery; a cover having hinge-connection with said battery case; an electric lamp mounted in said cover and positioned to illuminate said base; another electric lamp mounted in said cover and positioned to direct light beyond the same; a contact strip carried by the outer end of said battery; another contact strip secured to said battery case, suitable wiring connecting said lamps and said second mentionel contact strip with said battery, and a suitable contact strip carried by said cover and designed to come into contact with said other contact strips when said cover is opened far enough so as to close said circuit to light said lamps.

In testimony whereof we have affixed our signatures in presence of two witnesses.

FRANKLIN JOSEPH WHITNEY.
PHILLIP SHURDEN HALL.
